Application July 24, 1939, Serial No. 286,128

13 Claims. (Cl. 242—43)

The present invention relates to new and useful improvements in winding machines, and more particularly to a novel and improved quick traverse winding machine particularly adapted for winding tapered end packages on a tapered, conical, cylindrical or tubular core.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate modifications of the invention, and together with the description, serve to explain the principles of the invention.

Of the drawings:

Figure 1 is a fragmentary side elevation of the lower portion of a typical and illustrative embodiment of the present invention;

Figure 2 is a fragmentary end elevation of the parts shown in Figure 1;

Figure 3 is a fragmentary side elevation of the winding head of the illustrative embodiment;

Figure 4 is an end elevation of the parts shown in Figure 3 but showing the parts in their relation to a substantially fully wound package;

Figure 5 is a sectional view taken on the line 5—5 of Figure 3;

Figure 6 is a sectional view taken on the line 6—6 of Figure 5;

Figure 7 is a detailed end view of certain of the parts with some of the parts shown in section;

Figure 8 is a plan view of certain parts of the present embodiment of the invention, with the yarn guide and some of its associated parts being shown in two positions;

Figs. 9, 10 and 11 are fragmentary detail views showing modified forms of one of the parts;

Figs. 12, 13 and 14 are views showing different and illustrative forms of packages which may be wound with the embodiment of the present invention;

Fig. 15 is a fragmentary end view, with certain parts in section, of a modified form of the present invention; and

Fig. 16 is a plan view of the modification shown in Figure 15.

The present invention has for its object the 55

provision of a novel and improved winding machine particularly adapted for the rapid and accurate winding of yarn or thread on varied cores to form packages which are tapered at either 5 or both ends. A further object of the invention is the provision of an attachment which may be applied to winding machines of substantially conventional construction to adapt them to the winding of such packages. The invention also 10 provides means for controlling the traverse of the yarn or thread guide from its driving means so that the relative extent of their movement may be varied and kept under constant control, as by the diameter of the package being wound. A 15 further object of the invention is the provision of a winding machine which may be easily and simply adjusted so as to positively control the formation of the package ends so as to produce a definite and predetermined shape of package. Still another object of the invention is the provision 20 of a yarn traverse mechanism which can be controlled so as to traverse the yarn for a longer or shorter distance than the regular cam and primary traverse parts. The invention has for a 25 further object the provision of a simple, light and inexpensively manufactured, dependable yarn winding machine which can be operated at relatively high speeds.

In accordance with the illustrative embodiment 30 of the present invention, means are provided for positively rotating the core at a relatively high speed while it is supported on a driven spindle, and this spindle is preferably located near the top of the machine frame where it is easily accessible. Gated to the spindle and driven therewith are cam means for reciprocating a traverse member at a relatively constant velocity, and this member is supported on a pivotally or swingably mounted frame so that it may move from 35 the package as the package builds up through the winding of yarn on the core.

A thread guide is reciprocably carried by the pivoted or swinging frame and is moved back and forth at a relatively constant distance from the 40 surface of the package or even against the surface of the package, the distance being maintained in the illustrative embodiment by means of a roller or other member mounted on the frame, bearing against the surface of the package and supported between the package and the thread guide.

Means are provided for interconnecting the cam driven reciprocating member and the thread guide so that the thread guide is driven from the cam, and as embodied the reciprocating

member, or traverse rod, is pivotally connected with a lever having a fixed fulcrum, and intermediate its ends this lever is slidably and pivotally connected with a superposed lever which is slidably and pivotally connected at one of its ends and is connected with a pivot at its other end so that as the cam moves the traverse rod, the oscillation of the first lever is transmitted to the second lever to cause its oscillation through a variable angle. By shifting the pivots of the second lever, the extent of traverse of the thread guide may be minutely, accurately and positively controlled while the reciprocation of the traverse rod remains constant.

Means are provided whereby the movement of the swinging frame away from the spindle as the diameter of the package increases is transmitted to the interconnected lever system so as to vary the position of one of the pivots and thereby cause the extent of the traverse of the thread guide to vary in accordance with the package diameter. In this way, the ends of the package may be tapered at either or both ends, and by selecting the position of one of the pivots the initial traverse of the thread guide may be made shorter or longer than the reciprocation of the cam driven traverse member.

In accordance with a modified embodiment of the invention, the diametral control of the shiftable pivot of the interconnected lever system may be effected through a universal joint connected with one of the levers, and resilient means may be provided at each end of the traversing stroke of the thread guide to absorb the shock necessarily attendant upon a quick reversal in the direction of travel of the thread guide at each end of its stroke as well as to assist in the quick reversal movement of the guide.

It will be understood that the foregoing general description of the invention and the following detailed description as well, are exemplary and explanatory of the invention but are not restrictive thereof.

Referring now in detail to the illustrative embodiment as shown in the accompanying drawings, the invention is shown as applied to a standard winding machine generally known in the trade as the "Foster precise winder." On the main frame 1 is rotatably mounted a drive shaft 2 which may be driven by a motor 3 through pulleys 4 and 5 and belt 6, and one or more winding heads 7 may be mounted at the upper part of the frame. Each of the winding heads comprises a housing 8 in which is mounted the main traverse cam 9 rotatably mounted and driven by the shaft 10 journalled in the housing 8.

Means are provided for rotatably supporting and driving a tube or tapered core and comprise a spindle 12 rotatably mounted in the spindle bearing housing 13. This spindle is variably positionable on the top of the housing 8 so as to accommodate different tapers of cores or tubes and is provided with a manually operated means for holding and releasing the cores 14 on which the yarn or other strand-like material may be wound to form self-supporting packages 15. For driving the spindle 12, the drive shaft 2 in the lower portion of the frame is provided with pulley 16 to drive the belt 17, and cam shaft 10 is driven from the spindle by means of a gear train 18 in the conventional manner.

Cam 9 reciprocates a traversing element 21 slidably mounted on a round traverse bar 20 which is reciprocably supported in a cast-iron 75

guideway 11 which is swingably supported by two arms mounted on the cam shaft bushings in the housing. The traverse bar 20 carries a traversing element 21 provided with a stud 22 and a cam roller 23 which fits into the groove of cam 9 so as to reciprocate the traverse element 21 in any positions of the guideway 11 as the cam rotates, the guideway being capable of being swung toward and away from the core supporting spindle 12.

A thread guide or yarn traversing guide 37 is mounted on the swinging frame and is reciprocable along the core on which the yarn is wound. The traversing element 21 is provided with a flat upright extension 24 which is supported on one side by an upright back 25 and on its other side by a steel plate 26, 25 and 26 forming parts of the guideway 11 which keeps the traverse element 21 in a predetermined relative position with reference to the other parts mounted on the swinging frame.

The primary traverse element 21 is further provided with a flat lower extension 27 to which is fastened a stud 28 carrying the upper end 30 of a lever or bar 29 which is freely pivoted on the stud 28 while the lower end 31 of the lever 29 is pivotally supported by a stud 32 held in a fixed position with reference to the swinging frame by means of a rigid depending bracket 33. Bracket 33 is preferably formed so as to provide for various positions of the stud 32, and may be formed as shown in Figures 9, 10 or 11. In Figure 9 the holes 34A, 34B and 34C are provided giving three different fixed positions of the stud 32, while in Figure 10 an elongated slot is provided and Figure 11 shows an elongated slot 35A provided at each end with screw means for variably locating the stud 32 in the slot.

As cam 9 is rotatably driven, the primary traversing element 21 is reciprocated longitudinally of the spindle 12, the upper end 30 of the lever 29 is similarly carried back and forth for the full extent of the throw of cam 9, while the lower end 31 is held about the fixed but variably positionable pivot 32. Lever 29 is preferably formed of two telescoping parts, as a rod and a tube, one slidably engageable within the other so as to accommodate the changing distance between the studs 28 and 32.

Yarn guide 37 is slidably mounted on the round guide rod 38, which is reciprocable in a fixed path with reference to the swinging frame and guideway 11. Yarn guide 37 is formed with an upright extended portion 37A which is supported by the front side of the steel plate 26 while the back side of plate 26 contacts the front of the upright extension 24 of the primary traverse mechanism and the upright extension 37A of the yarn guide 37 is held in alignment by means of another steel plate 39, bearing against and frictionally engaging the front face of the traverse guide upright 37A so that the upright 37A may slide between the plates 26 and 39.

Bearings 40A and 40B, one at each end of the plate 39, support the guide rod 38, and both traverse bar 20 and guide rod 38, as well as the plates 26 and 39, are removably held in a fixed position on the swingable guideway 11.

Yarn guide 37 is provided with a depending extension 37B which extends downwardly for a sufficient distance to form a pivotal support for the swivel 41. Swivel 41 is provided with a cylindrical bore at right angles to its pivoting axis and is adapted to receive and slidably engage the upper end 42A of a round bar 42. The

ower end 42B of the bar 42 is slotted as at 42C, his slot extending longitudinally of the bar so that the bar may be pivotally and slidably supported on a shouldered swivel stud 43, this stud being provided with a shoulder bearing 44 on one side of the slotted rod and a nut 45 on the other side which is tightened on the stud but allows free sliding of the slotted rod 42. Swivel stud 13 is further provided with an internal bearing extending at right angles to its axis for slidable and rotatable engagement with the outer and depending end 47 of a lever 46, which is supported by a bracket 48 fastened to the front outer side of the housing 8. Bracket 48 is provided with two projecting lugs 49A and 49B formed with alined bearing apertures to provide spaced apart bearings for the rod 46 held against axial movement by means of the collars 46B and 46C.

Means are provided for oscillating lever 46, and these means comprise a lever 50 extending upwardly from the rod 46 provided with a series of holes 50A, 50B, etc., any one of which may be selected to provide a different lever ratio on the lever 50. Means are provided for varying the position of the lever 50 and thereby the pivot 43 in accordance with the position of the swinging frame and guideway 11, and for this purpose a link 51 is pivotally connected with the lever 50 by means of stud 53 and block 54, while the upper end of the link 51 is bent to form a hinge joint 51A attached to and movable with the swinging guideway 11. Block 54 is formed with a bearing aperture so that the block is pivoted on the stud 53, and is further provided with a plain smooth hole positioned to receive the end of link 51 held in a definite position therein by means of the nuts 52A and 52B.

Means are provided for interconnecting the secondary traverse mechanism and thread guide which has just been described with the primary traverse mechanism so that the secondary traverse mechanism and thread guide are driven from the primary traverse mechanism and from the cam 9. For this purpose a bracket 57 is fastened by a set screw 57' to the upper end of the round tubular lever 29, and on its side surface bracket 57 is formed as a disc-like surface 57A to which is pivotally connected a guide 58 through which passes the rod-like portion of bar 42. Rod 42 is held against endwise movement relatively to the bracket 57 by means of the collars 56A and 56B which do not interfere with the oscillation of the rod 42, and slide 58 is pivotally held to the bracket 57 by means of the nut 58C.

Means are provided for moving the swinging frame and guideway 11 and the parts carried thereby including the yarn guide 37 away from the spindle 12 progressively as the package builds up through the winding of yarn on the core 14. For this purpose a roller 80 is freely rotatable in a yoke 81 which is pivotally mounted on the upper portion of the guideway 11 by means of a pivot 82, the roller normally lying against the surface of the package or core and extending parallel thereto. Roller 80 is positioned between the yarn guide 37 and the spindle 12, and while of relatively small diameter substantially fills the space between the yarn guide and the adjacent surface of the package, thereby providing a substantially frictionless member to engage the surface of the package for the movement of the frame 11 away from the package. Frame 11 is resiliently held against movement away from the package by means of a pressure spring 84

supported on a bracket 85 extending from the front of the housing 8 and connected at its other end to some part of the frame 11.

As is customary, the spindle 12 is rotated at a relatively high speed, and the cam 9 is rotated at some fraction of the spindle speed, and suitable provision may be made, if desired, for gainage or lossage so that the strands do not lie directly on top of each other, thereby avoiding piling. When the spindle is run in the direction shown by the drawings, the yarn is led through the opening in the yarn guide 37, across the upper surface of roller 80, and on to the downwardly moving adjacent side of the package 15.

As the spindle 12 rotates at a relatively high speed carrying with it the package core for package 15, and the cam 9 rotates at a lower speed, the traverse element 21 is moved back and forth by the cam 9, thereby driving the traverse element and the lower extension 27 mounted near the end of the traverse element 21. Bar 29 is thereby oscillated about its pivot 32, its upper end 30 sliding back and forth within the tubular portion of the bar 29, and this oscillation of the primary traversing element is transmitted to the secondary traversing element through the pivoted and slidable connection 57, 58 to oscillate the secondary traversing mechanism about the universal joint 43, 44, 45. The upper end of the bar 42 of the secondary traverse mechanism is slidably mounted in swivel 41, and drives the yarn guide 37A, 37C to reciprocate it in a straight line back and forth across the facing of the package 15. Yarn guide 37A, 37C is maintained at a constant distance from the surface of the package by means of the roller 80, and the normal spring tension serving to hold the swinging frame. As the package builds the roller 80 is urged away from the spindle 12 and takes the yarn guide and the other parts mounted on the swinging frame along with it. This building of the package moves link 51 and gradually swings lever 50 in a clockwise direction about its supporting shaft 46, the lower end of this shaft 46 being connected to a shouldered swivel stud 43 which is slidable in a slot 42C formed as the lower portion of rod 42. Thereby an increase of the diameter of the package causes swivel stud 43 to be moved downwardly away from the interconnecting pivot between the primary and secondary traverse mechanisms and lengthening the effective portion of the lever below its pivot, thereby reducing the length of reciprocation of the yarn guide 37. The length of the lever 29, 30 does not vary with the size of the package, nor does the length of the upper portion of the lever 42, but the shortening of the traverse is effected by the increase in length of the lower portion of the lever 42.

The extent of the shortening of the traverse of the yarn guide with an increasing package diameter can be precisely controlled by connecting the rod 51 to lever 50 through one or the other of the holes 50A, 50B.

When it is desired to wind a package of the type shown in Fig. 13, this may be accomplished by placing the pivot stud 32 in hole 34C of the bracket of Figure 9, or by shifting the pivot to the right in the slots 35 or 35A of Fig. 10 or 11. The taper may be formed on the nose of the package by shifting the pivot to the left as to hole 34A of Fig. 9.

Figures 15 and 16 illustrate a modified embodiment of the invention in which resilient means are provided for absorbing the shock of sudden

reversal of the yarn guide and assist in the reversal of the yarn guide. As embodied, the parts are largely similar to those previously described in detail but springs 70A and 70B are coiled about the yarn-guide and guide rod 38, one on each side of the yarn guide lower extension 37B and between the yarn guide and the bearings 40A and 40B. Springs 70A and 70B are of such a length that they are compressed towards the ends of the yarn guide reciprocating stroke and as the yarn guide reverses its movement they tend to accelerate the initial movement of the guide. While the springs may be left free on the rod 38, they are preferably secured by their adjacent end to the yarn guide extension 37B or to the bearing brackets 40A or 40B.

Figures 15 and 16 also show a modified embodiment of the secondary traverse mechanism. As shown, a bracket 59 having split lugs 59A and a tightening screw 59B is clamped on the upper end of the primary traverse tube of lever 29 and extends upwardly to provide a disc-like seat 59C on which is pivotally mounted a sleeve 68, through which passes the rod 60 held against axial movement in the sleeve by means of the set screw 68D. The upper end of the lever rod 60 passes through the swivel 41 which connects it with the yarn guide as in the previously described embodiment while the lower end of the rod is slidably received within a tubular member 62 which is provided at its lower end with a lug 62A hinged to the lug 64A by means of the pivot screw 63. Extending laterally from the lug 64A is a tubular member 64 which fits over and is rotatable on the depending and angularly movable rod-like arm 61 which is bent to provide a horizontally extending portion 61A journaled in the ends 66A and 66B of the bracket 65, and is held against axial movement by means of the collars 67A and 67B.

For oscillating the rod 61A and thereby moving the pivoting hinged lugs 64A and 62A along the rod 60 in accordance with the building of the package and the falling away of the frame and guideway 11, link 69 connects the frame supported arm 69A with lever 50 which is fast to shaft or rod 61A. Link 69 passes through a lug 75 and its effective length may be altered by means of the jamb nuts 76, while lug 75 is pivotally secured to one or the other holes in lever 50 by means of the screw 77.

In operation, the secondary traverse mechanism of Figures 15 and 16 is similar to that of the previously described embodiment.

The invention in its broader aspects is not limited to the specific mechanisms shown and described but departures may be made therefrom within the scope of the accompanying claims without departing from the principles of the invention and without sacrificing its chief advantages.

What we claim is:

1. A winding machine including in combination a rotatable spindle to support and rotate a core, a swinging frame to be moved away from the spindle and core as the package builds up on the core, a reciprocable traverse rod carried by the frame, a thread guide carried by the frame driven from the traverse rod and traversable back and forth in a straight line along the core and means interconnecting the thread guide and traverse rod for varying the length of traverse of the thread guide.

2. A winding machine including in combination a rotatable spindle to support and rotate a core,

a swinging frame to be moved away from the spindle and core as the package builds up on the core, a traverse rod carried by the frame, a thread guide carried by the frame and traversable back and forth along the core, lever means interconnecting the traverse rod and thread guide and means controlled by an increase in the diametral dimension of the package for varying the lever ratio of the lever means to reduce the length of traverse of the thread guide as the package builds up on the core.

3. A winding machine including in combination a rotatable spindle to support and rotate a core, a swinging frame to be moved away from the spindle and core as the package builds up on the core, a traverse rod carried by the frame, a thread guide carried by the frame and traversable back and forth along the core, a pair of levers interconnected with each other and connecting the traverse rod with the thread guide and means for variably positioning the fulcrum of at least one of the levers to vary the length of traverse of the thread guide relative to the traverse rod.

4. A winding machine including in combination a rotatable spindle to support and rotate a core, a swinging frame to be moved away from the spindle and core as the package builds up on the core, a traverse rod carried by the frame, a thread guide carried by the frame and traversable back and forth along the core, a pair of levers slidably and pivotally interconnected by means of a pivot relatively movable lengthwise with respect to one of the levers, a fixed pivot for one lever, a movable pivot for the other lever and one of the levers being connected to the traverse rod while the other lever is connected to the thread guide and means for moving the second movable pivot.

5. A winding machine including in combination a rotatable spindle for rotatably supporting and driving a core, a frame having relative movement with respect to the rotating core as the package builds up on the core, a traverse rod carried by the frame and movable back and forth relative to the core, a thread guide reciprocable in a straight line back and forth along the core at a relatively constant distance from the package and variable ratio lever means interconnecting the thread guide and traverse rod for varying the length of traverse of the thread guide.

6. A winding machine including in combination a rotatable spindle for rotatably supporting and driving a core, a frame having relative movement with respect to the rotating core as the package builds up on the core, a traverse rod carried by the frame and movable back and forth relative to the core, a thread guide movable back and forth along the core at a relatively constant distance from the package, variable ratio lever means interconnecting the thread guide and traverse rod for varying the length of traverse of the thread guide and means operative near the ends of the thread guide movement for assisting reversal of the thread guide movement.

7. A winding machine including in combination a rotatable spindle for rotatably supporting and driving a core, a frame having relative movement with respect to the rotating core as the package builds up on the core, a traverse rod carried by the frame and movable back and forth relative to the core, a thread guide movable back and forth along the core at a relatively constant distance from the package, variable ratio lever means interconnecting the thread guide and traverse rod for varying the length of traverse of the

thread guide and springs compressed by the thread guide reciprocation near the ends of its movement.

8. A winding machine including in combination a rotatable spindle to support and rotate a core, a swinging frame to be moved away from the spindle and core as the package builds up on the core, a traverse rod carried by the frame, a thread guide carried by the frame and traversable back and forth along the core, a pair of levers interconnected with each other and connecting the traverse rod with the thread guide and a variably positionable universal joint slidably connected with one end of one lever and forming the fulcrum of that lever to vary the length of traverse of the thread guide relative to the traverse rod.

9. A winding machine including in combination a rotatable spindle to support and rotate a core, a swinging frame to be moved away from the spindle and core as the package builds up on the core, a traverse rod carried by the frame, a thread guide carried by the frame and traversable back and forth along the core, a pair of levers slidably and pivotally interconnected by means of a pivot relatively movable lengthwise with respect to one of the levers, a fixed pivot for one lever, a movable universal joint forming a pivot for the other lever and one of the levers being connected to the traverse rod while the other lever is connected to the thread guide, means operated by movement of the frame for moving the movable pivot to vary the length of traverse of the thread guide.

10. A winding machine including in combination means for rotatably supporting and positively driving a core, a frame movable away from the core as the package builds up, a traverse rod carried by the frame and reciprocable relative to the length of the core, a thread guide reciprocable across the length of the core and means interconnecting the thread guide and traverse rod for varying the length of traverse of the thread guide, and means controlled by the size of the package for effecting the variation including a link connected to the frame, a lever oscillated by the link and a shiftable pivot moved by the lever and forming part of the interconnecting means.

11. A winding machine including in combination a rotatable spindle to support and rotate a

core, a swinging frame to be moved away from the spindle and core as the package builds up on the core, traverse means carried by the frame, a thread guide carried by the frame and traversable back and forth along the core and means interconnecting the thread guide and traverse means for varying the length of traverse of the thread guide, said interconnecting means including a lever driven by the traverse means, a second lever adjacent thereto and lying along the first lever, a pivot fixed to both levers, a sliding pivot slideable along one lever and a sliding connection between the second lever and thread guide.

12. A winding machine including in combination a rotatable spindle to support and rotate a core, a swinging frame to be moved away from the spindle and core as the package builds up on the core, traverse means carried by the frame, a thread guide carried by the frame and traversable back and forth along the core, lever means interconnecting the traverse means and thread guide and means for varying the lever arm ratio of the lever means as the swinging frame is moved away from the core by the building of the package, said interconnecting means including a lever driven by the traverse means, a second lever adjacent thereto and lying along the first lever, a pivot fixed to both levers, a sliding pivot slideable along one lever and a sliding connection between the second lever and thread guide.

13. A winding machine including in combination a rotatable spindle to support and rotate a core, a swinging frame to be moved away from the spindle and core as the package builds up on the core, traverse means carried by the frame, a thread guide carried by the frame and traversable back and forth along the core, lever means interconnecting the traverse means and thread guide and means controlled by the size of the package for varying the lever ratio of the lever means to reduce the length of traverse of the thread guide as the package builds up on the core, said interconnecting means including a lever driven by the traverse means, a second lever adjacent thereto and lying along the first lever, a pivot fixed to both levers, a sliding pivot slideable along one lever and a sliding connection between the second lever and thread guide.

ALFRED W. ARTERTON.
